DESIGN FOR A CASING FOR MUSICAL INSTRUMENTS.

SPECIFICATION forming part of Design No. 32,434, dated April 3, 1900.

Application filed March 7, 1900. Serial No. 7,731. Term of patent 14 years.

To all whom it may concern:

Be it known that I, GUSTAV A. BRACHHAUSEN, a resident of Rahway, Union county, State of New Jersey, have invented and produced a new, useful, and original Design for a Casing for Musical Instruments, of which the following is a specification, reference being had to the accompanying drawings, wherein—

Figure 1 is a front view of a casing for musical instruments embodying my design. Fig. 2 is a transverse sectional view of the same, taken on the line 2 2 of Fig. 1.

The characteristic feature of my design consists in a casing having a curvilinear front wall.

In the accompanying drawings, *a* indicates the base of the casing proper, which supports the upright walls *b*, and the upright walls are surmounted by a top or cover *c*.

The front wall *A* of the casing is curvilinear 20 in form, the curvature extending outwardly from each side of the casing to the center thereof.

I claim—

The design for a casing for musical instruments, substantially as shown and described.

GUSTAV A. BRACHHAUSEN.
